METHOD OF AND MEANS FOR ATTACHING
PRINTING MEMBERS TO CYLINDERS OF
PRINTING PRESSES

George S. Rowell, Bedford, and Herbert McGeorge, Cleveland Heights, Ohio, assignors to The Chandler & Price Company, Cleveland, Ohio, a corporation of Ohio.

Application November 1, 1946, Serial No. 707,290

18 Claims. (Cl. 101—415.1)

1

This invention relates, as indicated, to lithographic plates and the like and means for attaching the same to cylinders of cylinder printing presses.

Lithographic or planographic plates of the type now currently employed may be of thin metal, metal foil, cellulose (paper), or plastic. They have ordinarily been attached to the cylinder of the press by punching a row of holes along the leading and rear edges of the sheets and hooking such edges over corresponding rows of teeth carried on the recessed non-printing portions of the cylinder. Or the ends of the plate have been clamped between opposed bar members in such recesses and the plate sharply bent over the edges of the recesses. Such attaching means have long been a source of much trouble for the operator. The holes in the plate wear rapidly and become elongated or torn so that the plate either becomes loose while the press is in operation or gets out of register so that a non-uniform product is obtained. The metal plates, particularly, often become so permanently deformed as to render storage a problem.

It is, therefore, a primary object of our invention to provide a lithographic plate and attaching means adapted to cooperate therewith to ensure both proper registry and secure attachment in use.

Another object of this invention is to provide attaching means for lithographic plates which will be adaptable for use with both cellulose (paper) and metal plates.

Still another object is to provide attaching means of the type indicated which will not damage the plate either in use or when attaching or detaching such plate.

Other objects of our invention will appear as the description proceeds.

To the accomplishment of the foregoing and related ends, said invention then comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawings:

Fig. 1 is a sectional view transversely of the cylinder and plate attaching means mounted thereon;

Fig. 2 is a top plan view of one of such plate attaching means;

Fig. 3 is an elevational view of such attaching means;

Fig. 4 is a fragmentary sectional view of one end of such attaching means;

Fig. 5 is a top plan view of the end portion of a lithographic plate or the like adapted to cooperate with our new attaching means;

Fig. 6 is a top plan view of the top member of such attaching means;

Fig. 7 is a top plan view of the intermediate member of such attaching means;

Fig. 8 is a top plan view of the lower member of such attaching means;

Fig. 9 is a fragmentary bottom plan view of such top member;

Fig. 10 is a vertical sectional view of the resiliently mounted form of our new attaching means illustrating the position of such intermediate member when a cellulose lithographic plate is employed, for example;

Fig. 11 is a view of such attaching means similar to that of Fig. 10 but illustrating the position of the intermediate member when a metal lithographic plate is employed;

Fig. 12 is a vertical sectional view through such attaching means showing the projections serving to register the lithographic plate;

Fig. 13 illustrates one mechanism for opening and closing the attaching means;

Fig. 14 is a view similar to Fig. 13 but showing the device in closed position;

Fig. 15 is a vertical sectional view taken along the line 15—15 on Fig. 14;

Fig. 16 is a sectional view of another embodiment of my invention in which the holding teeth are adapted to be retracted into the cylinder;

Fig. 17 is a sectional view similar to Fig. 16 but showing the teeth extended;

Fig. 18 is a sectional view taken along the lines 18—18 on Fig. 16;

Fig. 19 is an end elevational view of such clamping means;

Fig. 20 is a top plan view of such clamping means;

Fig. 21 is a vertical sectional view taken along the line 21—21 on Fig. 20; and

Fig. 22 is a detail view of a portion of the teeth operating means.

Referring now more particularly to such drawings and especially Figs. 1-3, the device of our invention is adapted to be mounted on appropriately recessed portions of the plate cylinder 1 of a rotary press. One of such attaching means is fixedly positioned on the cylinder while the other is resiliently mounted to facilitate attachment of the lithographic plate and to insure that such plate is held about the cylinder under proper tension. Each of such attaching means com-

prises a lower member 2 secured to the recessed portion of the cylinder and carrying a row of beveled teeth 3. An intermediate plate 4 is apertured to fit over such teeth and rest upon lower member 2. An upper member 5 is pivotally attached at 6 to the rear edge of member 2 and is likewise apertured to fit over the ends of beveled teeth 3.

In addition to upstanding teeth 3, lower member 2 is also provided with upstanding V-shaped registry lugs 7 (see Figs. 8 and 12) which are adapted to cooperate with V-shaped notches 8 in the leading and rear edges of the lithographic plate 9 (see Fig. 5). Intermediate member 4 is notched at 10 and top member 5 is apertured at 11 to receive such lugs when the attaching means is in closed position.

We are aware that lithographic plates have been made in the past with a large number of tabs at each end and a hole through each tab for attaching to hooks. Such an arrangement has proven disadvantageous for a number of reasons including the fact that such tabs become bent and torn in use. Also, the number of holes available to be secured to the attaching hooks or teeth is greatly reduced and the strength of the plate is not as great as one having a relatively unbroken edge. In our lithographic plate, as illustrated in Fig. 5, the plate is provided with a plurality of holes between the registering V-shaped notches, thereby providing a maximum of holding power without weakening the edge portion of the plate. Where an individual tab is provided for each such hole they become bent and tend to prevent the plate from being held flat against the glass of a vacuum printing frame. Furthermore, there is waste in the excess material cut away to form such tabs, adding to the cost of the plates. With our arrangement the holes may be closer to the ends of the plate without danger of tearing whereas in the case of tabs extra material must be left about each hole.

Adjacent each end of intermediate member 4 are holes 12 and 13 through which protrude posts 14 and 15, respectively, coil springs such as 16 tending to urge intermediate member 4 upwardly. Clamping means are provided operative to hold the members of the plate attaching means in close engagement. Such clamping means comprises four similar units, each of which consists of a post 17 secured in the cylinder and extending upwardly through an opening 18 in top member 5. Posts 17 have raised caps 18', the under portions of which are engaged by inclined slides 19. Coil springs 20 tend to urge member 5 and therefore such slides upwardly against the under portions of such caps 18'. Rods 21 and 22 connect such slides to cam followers 23 and 24, respectively, adapted to travel in cam tracks 25 and 26 of rotatable table 27. Thus, by rotating such table, rods 21 and 22 may be reciprocated similarly to reciprocate inclined slides 19. When the lowermost portions of the inclined portions of such slides are beneath caps 18' of posts 17, it is obvious that springs 20 will thereby be enabled to elevate top plate 5 to clear teeth 3. The coil springs encircling posts 14 and 15 (see Figs. 2 and 4) will likewise be effective to raise the intermediate plate 4 above the level of the ends of such teeth.

As above indicated, the attaching means of this invention may be made as a separate unit to be secured to the impression cylinder or the lower member 2 may be formed integrally with such cylinder. In any case, however, one of such at-

taching means should be resiliently mounted to facilitate attachment of the lithographic plate and also to insure proper tensioning thereof. The attaching means shown to the left in Fig. 1 of the drawing, while otherwise identical with the attaching means securing the other end of the plate, is thus resiliently mounted. The base of the recess in cylinder 1 is cut away to leave an upstanding lip 28 (see Figs. 1 and 3) and a horizontal slot 29 to the rear of such recess (see Figs. 10, 11 and 12). A block 30 of lesser width than such cut away portion is slidably mounted in the bottom of the recess behind lip 28 and is urged rearwardly therein by coil springs 31 encircling screws 32 threaded in such lip portion 28 of the recess. Block 30 is thus urged rearwardly by such springs into slot 29 but may be forced toward lip 28 against the compression of springs 31 when it is desired to secure a lithographic plate in the attaching means.

The under surface of top member 5 is longitudinally scored by two shallow grooves 33 and 34 and one surface of intermediate member 4 is provided with ridges 35 and 36 corresponding to such grooves when such members are assembled (see Fig. 10). Member 4 is reversible so that when desired the said ridges 35 and 36 may be turned downwardly out of cooperative relation to grooves 33 and 34 (see Fig. 11).

An alternative device for clamping and unclamping the attaching means is illustrated in Figs. 13-15, inclusive. When employing this form of clamping means, the teeth 3 will desirably be secured in upper member 5 rather than in member 2. A side plate 37 is pivotally attached at 38 to the end of bottom member 2 and is provided with a handle 39. Studs in the form of screws 40 and 41 secured to the ends of members 5 and 4, respectively, engage cam tracks 42 and 43, respectively, in such pivotally mounted side plate 37. Such cam tracks are so formed that when handle 39 is shifted from the Fig. 14 to the Fig. 13 position, intermediate member 4 is first held in position relative to lower member 2 while top member 5 is elevated. When such pivotal movement has progressed far enough to elevate top member 5 sufficiently to withdraw the ends of teeth 3 into the thickness of intermediate member 4, cam track 43 causes member 4 likewise to be elevated sufficiently to release the lithographic plate 9.

The operation of our new attaching means may now be described. Table 27, which may be provided with a knurled rim, is turned to draw slides 55 19 toward the same, thereby permitting springs 20 to elevate top member 5 above the ends of teeth 3 and to permit the springs about posts 14 and 15 likewise to elevate intermediate member 4 until the upper surface of such member is above 60 the ends of such teeth. If a cellulose lithographic plate is to be employed, member 4 is turned with its ridges 35 and 36 directed upwardly to cooperate with grooves 33 and 34 in the under surface of top member 5 (see Fig. 10). The end of plate 9 is then inserted between members 4 and 5 with the notches 8 in such plate registered by V-shaped lugs 7. Cam table 27 is now rotated in the opposite direction to cause slides 19 to ride under caps 18' of posts 17 and thereby depress top member 5, the lithographic plate 9 and the intermediate member 4. As such member is thus depressed, the end portion of lithographic plate 9 is first clamped between members 4 and 5, and member 4, the plate 9 and member 5 slide down teeth 3 as a unit, such teeth passing first through

5

holes 44 in member 4 and holes 45 in plate 9 and finally holes 46 in top member 5. The other end of the lithographic plate is similarly secured in the other resiliently mounted attaching means, sliding block 30 being moved toward lip 28 against the force of compression springs 31 to facilitate the operation. Such block is then permitted to slide rearwardly under the impulse of such springs to draw plate 9 tightly about the surface of the impression cylinder and to lock the rear edge of such block in groove 29. The plate is now ready for use.

When it is desired to remove the plate from the cylinder such removal may be effected without injury thereto, as follows. The resiliently mounted attaching means is pulled outwardly against the force of compression springs 31 to somewhat relax the tension on plate 9 and slides 19 are shifted to permit top member 5 to rise. Member 4 likewise rises under the urging of the springs around posts 14 and 15 and acts as a stripper plate to clear plate 9 of the ends of teeth 3. Such plate is held tightly between members 4 and 5 until it is clear of the ends of the teeth, whereupon, member 5 continuing to rise somewhat, the end of plate 9 may be withdrawn. The other end of the plate is then similarly released from the other attaching means. It will be seen from the foregoing that there is no danger of tearing the plate on the teeth as so often occurs with other forms of attaching means. The cooperating grooves and ridges of members 5 and 4 materially assist in the gripping of cellulose plates and the like both during the securing and removal steps and also during the actual printing.

In addition to resisting tension on the plate the clamping means hold such plate flat around the holes so that burring is prevented there.

When employing clamping means of the type illustrated in Figs. 13 and 14 the lithographic plate is firmly held between members 2 and 4 while top member 5 is raised or lowered. Thus there is no chance for the holes 45 in the plate to be torn as the ends of the teeth pass therethrough.

Referring now to Figs. 16-22 inclusive, there is illustrated another embodiment of our invention in which mechanism is provided for retracting the teeth into the cylinder. A saving of space is thereby obtained which may become important when it is desired that a maximum portion of the circumference of the cylinder be available for printing.

The recessed non-printing portion of the cylinder 1 is milled out to form a longitudinal slot 47 in the upper part of which a base member 48 is secured as by screws 49. The entire plate attaching mechanism is mounted on such base thereby greatly facilitating replacement and repair. Paired lever arms 50 and 51 are pivotally mounted on studs 52 and 53 respectively, projecting from the under surface and adjacent the ends of base 48. A bar 54 is carried pivotally between the ends of such arms, such bar being provided with a plurality of upstanding teeth 55 adapted to be reciprocated in a row of holes 56 in base 48. The other ends of arms 50 and 51 are pivotally connected to plunger rods 57 and 58 respectively provided with heads 59 and 60. Compression springs such as 61 beneath such heads act to hold teeth 55 normally retracted in base 48.

An upper clamping member 62 is hingedly attached to base 48 at 63 and 64 and is provided with a row of openings 65 corresponding to holes

6

56 in base 48 and adapted to receive the ends of teeth 55 when such ends are protruded from holes 56. The under surface of such bar is relieved in spaced areas to accommodate registry lugs 66 on base 48, such lugs corresponding in formation and purpose to lugs 7 above described. Reciprocably mounted in member 62 are plungers 67 and 68 adapted to bear upon the heads 59 and 60 respectively of plungers 57 and 58 when member 62 is in plate clamping position. Springs such as 69 bearing against the heads of plungers 67 and 68 hold them normally retracted in member 62. Mounted on the upper surface of clamping member 62 are two slides 70 and 71 having inclined faces such as 72 adapted to bear on the protruding heads of plungers 67 and 68. The outer extremities 73 and 74 of such slides extend beyond the end of member 62 when in advanced position for a purpose to be explained below. As best shown in Figs. 20 and 21 these slides are connected by rods 75 and 76 to a rotatable table 77 provided with a wing grip 78 whereby such slides may be reciprocated.

Means are provided at either end of base 48 for locking member 62 in clamping position comprising rods 79 pivotally mounted at 80 on base 48 and carrying hooks 81 slidable thereon. Nuts 82 on such rods serve to lock such hooks over studs 83 on member 62 to hold such member in clamping position. The extremities 73 and 74 of the slides will also overlie such hooks in this position when teeth 55 are extended, thereby necessitating reciprocation of such slides and retraction of such teeth before the clamp can be released.

The operation of this embodiment of our invention may now be explained. Clamping member 62 is raised and the lithographic plate registered on lugs 66. Member 62 is then lowered and locked in place by means of hooks 81 and nuts 82, thereby firmly gripping the lithographic plate. Slides 70 and 71 are now moved outwardly, camming down plungers 67 and 68 which in turn depress plungers 57 and 58 causing teeth 55 to be extended through the holes in the lithographic plate into holes 65 in member 62. As above pointed out, the slides must be withdrawn to retract the teeth before it is possible to unlock the clamping member.

If desired, one of the plate attaching means may be resiliently mounted in the cylinder, base 48 being mounted in the manner of block 30.

The same attaching means may be employed for securing the usual rubber "blanket" to a cylinder and will have not only the same advantages as above but will also be effective to take up the stretch in such blanket during use without the necessity of stopping the press to make adjustment. This is a very practical advantage as new blankets tend to stretch rather badly when first put in use.

It will be seen that we have provided novel attaching means for securing lithographic plates, blankets, and the like to the cylinders of rotary presses which will hold such plates very securely and in proper registry but which will not unduly deform the same or tear the leading and following edges. Such plates will therefore have a much longer useful life and need not have their edges reinforced or otherwise guarded. Furthermore, the attaching means is readily adaptable for use with either cellulose or metal plates.

Other modes of applying the principle of the invention may be employed, change being made as regards the details described, provided the

features stated in any of the following claims or the equivalent of such be employed.

We therefore particularly point out and distinctly claim as our invention:

1. Means for attaching lithographic plates, blankets, and the like to the cylinders of rotary presses comprising a plurality of teeth on such cylinder adapted to engage corresponding holes in such plate, clamping means operative to hold such plate firmly in engagement with such teeth, and a stripper member adapted to engage the other side of such plate from such clamping means and to cooperate therewith to clamp such plate therebetween during removal of such plate from said teeth.

2. Means for attaching lithographic plates, blankets, and the like to the cylinders of rotary presses comprising a row of teeth carried by such cylinder, a stripper plate slidably mounted on said teeth, and a clamping plate overlying said stripper plate operative to clamp the end of such lithographic plate or the like therebetween.

3. Means for attaching lithographic plates, blankets, and the like to the cylinders of rotary presses comprising a row of teeth carried by such cylinder, a reversible stripper plate slidably mounted on said teeth, such stripper plate being embossed on one surface, and a clamping plate overlying said stripper plate operative to clamp the end of such lithographic plate or the like therebetween.

4. Means for attaching lithographic plates, blankets, and the like to the cylinders of rotary presses comprising a row of teeth carried by such cylinder, a reversible stripper plate slidably mounted on said teeth, such stripper plate having locally embossed areas on one surface, and a clamping plate overlying said stripper plate operative to clamp the end of such lithographic plate or the like therebetween, said clamping plate having relieved areas corresponding to such embossed areas on said stripper plate.

5. Means for attaching lithographic plates, blankets, and the like to the cylinders of rotary presses comprising a row of teeth carried by such cylinder, a reversible stripper plate slidably mounted on said teeth, such stripper plate having a longitudinal ridge on one surface, and a clamping plate overlying said stripper plate operative to clamp the end of such lithographic plate or the like therebetween, said clamping plate having a groove in its under surface corresponding to such ridge on said stripper plate.

6. The method of securing the perforated end of a lithographic plate or the like to a cylinder of a press having corresponding teeth thereon which comprises first registering such end of such plate on such cylinder, next pressing such end to such cylinder in registered position while subjecting such sheet to lengthwise tension, and then inserting such teeth through such holes while such plate is held thus pressed against such cylinder.

7. The method of securing the perforated end of a lithographic plate or the like to a cylinder of a press having corresponding teeth thereon which comprises pressing such end between correspondingly perforated pressure members and then inserting such teeth in such perforations of such plate and pressure members while thus pressing such plate to secure the same against movement.

8. Means for attaching lithographic plates, blankets, and the like to the cylinders of rotary presses comprising a row of teeth carried by such

cylinder adapted to engage corresponding holes in such plate, clamping means carried by such cylinder operative to clamp such plate therebetween during relative movement of such plate and teeth, and projections on such cylinder adjacent said teeth adapted to engage notches in the edge of such plate to register such holes in such plate with said teeth prior to thus clamping such plate.

9. Means for attaching lithographic plates, blankets, and the like to the cylinders of rotary presses comprising a row of teeth carried by such cylinder, a stripper plate slidably mounted on said teeth, a clamping plate overlying said stripper plate operative to clamp the end of such lithographic plate or the like therebetween, resilient means respectively urging said stripper plate and said clamping plate out of engagement with said teeth, and cam means operative on said clamping plate first to move said clamping plate toward said stripper plate to clamp such lithographic plate therebetween and then to move such assemblage of plates into engagement with said teeth.

10. Means for attaching lithographic plates, blankets, and the like to the cylinders of presses comprising a row of holes in a recessed portion of such cylinder adapted to register with a corresponding row of holes adjacent an edge of such lithographic plate, a stripper plate adapted to overlie such holes similarly perforate, a member movably attached to such cylinder and carrying a plurality of teeth adapted to be inserted in such holes, and cam means operative first to move said movable member to withdraw such teeth from such holes and thereafter to raise said stripper plate from clamping position.

11. The method of securing the perforated end of a lithographic plate or the like to a cylinder of a press having corresponding teeth thereon which comprises tightly pressing such end to such cylinder and inserting such teeth through such holes while holding such plate thus tightly pressed to prevent shifting such plate due to tension thereon.

12. Means for attaching lithographic plates, blankets, and the like to the cylinders of a rotary press which comprises means adapted to register an edge of such plate on such cylinder, a plurality of teeth retractable into such cylinder, and means adjacent said teeth operative to clamp such plate.

13. Means for attaching lithographic plates, blankets, and the like to the cylinders of a rotary press which comprises a plurality of teeth retractable into such cylinder and means adjacent said teeth operative to clamp such plate.

14. Means for attaching lithographic plates, blankets, and the like to the cylinders of a rotary press which comprises a plurality of teeth normally held retracted in such cylinder, clamping means adjacent such teeth operative to clamp such plate, and means operative when said clamping means is in clamping position to extend said teeth from such cylinder.

15. Means for attaching a lithographic plate, blanket, or the like to the cylinder of a rotary press comprising a member movably secured to such cylinder having a plurality of teeth adapted to engage a plurality of holes in such plate and cylinder corresponding to such teeth, and a stripper member interposed between said toothed member and cylinder and adapted to hold such plate against said cylinder whereby damage to such plate may be avoided during the withdrawal of such teeth therefrom.

16. Means for attaching lithographic plates, blankets, and the like to cylinders of rotary presses comprising clamping members on such cylinder operative to clamp an end portion of such plate, another separate member secured to such cylinder having a plurality of teeth adapted to enter and engage corresponding holes in such plate, and means mounting said tooth bearing member for movement relative to said clamping members to withdraw such teeth from such plate prior to relaxing the grip of said clamping members on such plate, whereby distortion and tearing of such holes may be avoided.

17. Means for attaching lithographic plates, blankets, and the like to cylinders of rotary presses comprising clamping means on such cylinder operative to clamp such plate, teeth secured to such cylinder and insertable in corresponding holes in such plate, and means mounting said clamping means for movement bodily relative to said teeth, whereby said teeth may be inserted in and withdrawn from such holes while said clamping means is thus continuously clamping such plate.

18. Means for attaching lithographic plates, blankets, and the like to the cylinders of rotary presses comprising a row of teeth carried by such cylinder adapted to be engaged in complementary

5
10

holes in such plate, a clamping plate having an irregular surface opposed to a complementary member mounted on such cylinder adapted to hold the end portion of such lithographic plate therebetween while slightly crimping the same, and means mounting said clamping plate and complementary member for conjoint movement relative to said teeth axially of the latter, whereby such lithographic plate may be held firmly clamped between said clamping plate and complementary member during insertion of said teeth in and withdrawal of said teeth from such holes in such lithographic plate.

GEORGE S. ROWELL.
